(57) **CLAIM**

The ornamental design for a view of a driver disc cushion mount for a floor grinder or sander.

DESCRIPTION

FIG. 1 is a bottom perspective view of a driver disc cushion mount for a floor grinder or sander, in an environment of use, showing my new design.

FIG. 2 is a top perspective view thereof;

FIG. 3 is a bottom perspective view cushion mount shown in FIG. 1;

FIG. 4 is a top perspective view thereof;

FIG. 5 is a bottom plan view thereof;

FIG. 6 is a top plan view thereof; and,

FIG. 7 is a right side elevational view thereof.

The broken lines of a driver disc in FIGS. 1 and 2 are for the purpose of showing environmental structure, and form no part of the claimed design.
